CLOCK

Jack Bergman, 1327 Murdock Road, Pittsburgh, Pa.

Filed May 6, 1959, Ser. No. 55,798

Term of patent 14 years

(Cl. D42—7)

Fig. 1.

Fig. 2.

FIG. 1 is a perspective view of a clock showing the front and one side of my new design, the back being plain, and the hidden side a mirror image of the side shown; and

FIG. 2 is a transverse section through the casing showing the contour of the casing and the front of the clock.

I claim:

The ornamental design for a clock, as shown and described.
